EDGE-BINDING MACHINE

Worthington S. Bessett, Lynn, Mass., assignor to
 W. S. Bessett, Inc., Lynn, Mass., a corporation
 of Massachusetts

Application November 3, 1937, Serial No. 172,553

5 Claims. (Cl. 12—17)

This invention relates to a machine for applying an adhesive-coated binding tape to the edge of a flat article, such, for example, as the insole of a shoe.

Women's shoes have recently been made very extensively in the form of sandals or with open or skeletonized uppers leaving exposed to view more or less extensive portions of the edge of the insole. Insoles usually have an edge which cannot be finished or can only be finished with difficulty and at considerable expense, to present a finished appearance and consequently it is necessary to bind these edges with a material which will present a finished and pleasing appearance.

The present invention is particularly useful in providing a machine which operates to apply efficiently and economically a binding tape to the edge of the insole in which the tape presents on one side a suitable appearance, for example, being provided with a finishing coating such, for instance, as pyroxylon of the required color and presents on the other side a suitable adhesive coating.

An important object of the invention is in such a machine to provide a binder which will act to fold the tape into the shape required for applying it to the edge of the material so that it will surround the edge and the adjacent surfaces of the article to be bound with the adhesive coated surface presented thereto and in which the adhesive surface of the tape will be untouched by the binder during its passage therethrough. This is an important feature because the adhesive coated surface of the tape must be in a tacky condition

before it reaches binding position and if this tacky surface anywhere engages the binder, the tacky condition of the surface will be injured and any portion of the binder with which it comes in contact will be gummed up, further increasing the difficulty and the entire operation of the machine would be highly inefficient, if not impossible.

The invention has for its further object to provide a binder element in which the tape not only passes therethrough without contact of its adhesive-coated surface therewith but in which the tape is accurately guided and also may be readily and easily threaded or positioned in the binder.

The adhesive coating of the tape, in the broader aspects of the invention, may be of any well-known or suitable character and material. In any case, this adhesive coating before it reaches its point of application must be conditioned or brought into proper degree of adhesiveness so that it will properly adhere to the article to be

bound when applied thereto or pressed thereon. Such an adhesive coating may be, for example, of one of the well-known rubber cements and in this case the conditioning would be effected well before the tape reaches the binder by progressive application thereto of a suitable solvent properly to condition the adhesive coating. In the case, for example, of an adhesive coating formed of a vinyl resin or resins, the conditioning would also be effected well before the tape reaches the binder by progressive application of heat, as by an electric heater, to the coated surface or to the tape properly to condition the adhesive coating. In the case hereinafter more particularly described, the adhesive coating of the tape is a gutta-percha compound and it is conditioned at a point well before the tape reaches the binder by progressively forcing hot air against the coating to bring it into the required condition. In any case, however, the conditioning of the adhesive coating takes place well before the tape reaches the binder, thus giving the coating sufficient time partially to set or reach just the required tacky condition necessary for most efficient application when it reaches the article to be bound.

A further object of the invention is to provide, in the case of an adhesive coating such as that of a gutta-percha compound, where the conditioning is effected by hot air or other hot, gaseous fluid, an efficient means for forcing the hot, gaseous fluid under pressure against the adhesive coating. The employment of pressure for this purpose enables the means for supplying the hot, gaseous fluid to operate at a much slower speed than if a fan or other means were employed and insures a steady supply of heat to the coating.

These and other objects and features of the invention will appear more fully from the accompanying description and drawings and will be particularly pointed out in the claims.

The drawings illustrate a preferred form of the invention as embodied in a machine for applying an adhesive-coated tape of the character of a gutta-percha compound to the binding of the edge and immediately adjacent surfaces of an insole for shoes.

In the drawings:

Fig. 1 is a top plan view of the machine.

Fig. 2 is a side elevation.

Fig. 3 is a detail in side elevation of that portion of the machine where the binding takes place.

Fig. 4 is a front elevation of the construction shown in Fig. 3.

Fig. 5 is a top plan view of the binder or bind-

ing element removed from the machine with the tape indicated in dotted lines.

Fig. 6 is a cross section of a portion of the bound insole.

Fig. 7 is a detail partially in vertical cross section of the nozzle.

Fig. 8 is a view in side elevation illustrating a second form of mechanism for driving the machine.

10 The machine as illustrated is provided with a base, preferably formed of a single casting, comprising a bed or bottom plate 1, upstanding flanges 2 and 3 at the sides, and an upwardly and rearwardly inclined flange 4 at the front united with the side flanges.

15 The tape is fed through the machine and applied to the insole or other article and the article advanced by a pair of positively driven pressure feed rolls such as are well known in the art and need no particular description. The lower feed roll 5 is carried by a shaft mounted on a standard 6 projecting from the flange 2. This shaft at the right is also journalled in a boss projecting in from the flange 3 and is provided at its end with a gear 7. The upper feed roll 8 is carried by a shaft 9 journalled in a head 10 mounted for vertical movement in the standard 6. This head 10 is guided by a sleeve 11 extending downward therefrom into the standard 6 and by a dowel pin 12 also extending from the head into the standard. The head is yieldingly pressed downward by a spring, not shown, the force of which is adjustable by means of the set screw 13. The head 10 is raised to separate the feed rolls by any suitable means such as the lever 14 fulcrumed at 15 on the side flange 2, extending at its front end beneath the bottom of the sleeve 11 and at its rear end provided with a connection 16 extending down to a treadle or other suitable operating means.

20 To allow for the driving of the upper feed roll 8, notwithstanding its variation in vertical position, the shaft 9 on which it is carried is connected by a universal connection to the shaft 17 journalled in the boss 18 projecting from the flange 3. Such a connection is shown as a rod 19 carrying at its ends transverse pins 20 engaging transverse slots in the ends of the shafts 9 and 17. The shaft 17 at its outer end carries the gear 21 meshing with the gear 7 so that the two shafts rotate together in opposite directions as required by the usual feeding operation.

25 The feed rolls are shown as driven from a large gear 22 mounted on a shaft 23 and journalled in a projection from the flange 3. This shaft 23 carries a pinion 24 meshing with the gear 7. The gear 22 itself is driven by suitable means, two alternative forms of which will later be described.

30 The adhesive-coated tape 25 is wound upon a spool or reel 250 journalled on a shaft 26 between a pair of friction or tension plates 27 and 270. These plates are pressed against the spool or reel to give the necessary retarding friction by means of a spring 30 mounted on the shaft 26 between the plate 27 and a collar 31 adjustably secured to the shaft. The shaft 26 projects laterally from a bracket 28 projecting rearwardly from and secured at its base 29 to the main bed plate 1 of the machine.

35 The tape leads forward in a horizontal path beneath a suitable guide roller 32 projecting from the periphery of the plate 270 toward the front of the machine, turns into a vertical path and passes around a vertical guide pin 33 ex-

tending upward from the upper edge of the inclined flange 4. The finished or non-adhesive surface of the tape runs against the roller 32 and against the surface of the guide pin 33 and the tape in the construction shown conveniently passes between the feed roll shafts. From the guide pin 33 the tape passes to the binder.

40 The character and function of the binder are illustrated particularly in Figs. 3, 4, and 5. The binder is provided with a shank 35 by means of which it is mounted as by the set screw 36 on the front of the top of the standard 6 to position it properly with relation to the feed rolls. The binder essentially comprises an exposed, longitudinal, convex guide 37. This is conveniently a solid block secured to or forming a part of the shank and extends parallel with the axes of the feed rolls. The convex surface of this guide is preferably substantially equal to the width of the tape. A longitudinal edge guide extends at the base of the convex guide and preferably there are two such guides, being the vertical flat surfaces 38 and 39 extending respectively upward and downward at the base of the convex guide 37. Flanges 40 and 41 project forward above the longitudinal edge guides and are flared away from the convex guide at their right-hand ends. The tape is placed in this portion of the binder with its non-adhesive surface against the convex guide and with its edge against the longitudinal edge guide or, if there are two such longitudinal edge guides, then with the respective edges in engagement therewith. While the edge guides thus act by engagement with the edges of the tape to maintain it properly positioned in the binder, one or the other of the flanges 40 and 41 will act to force the tape back into position if the tape for any reason slips sidewise.

45 It will be seen that the convex guide is an exposed guide. That is, there is nothing between it and the adhesive-coated surface of the tape and as the flanges 40 and 41 are properly flared, the adhesive surface of the tape as the tape is in position over the convex guide is untouched. This convex guide acts, as the tape is drawn therewith, to bow the tape longitudinally. The binder further is provided with an exposed concave recess 42 in the end of the convex guide and extending substantially at right angles thereto and directly toward the feed rolls. As the tape, therefore, is drawn by the feed rolls back from the binder, the bow of the tape is reversed and the tape is presented with the adhesive-coated side inside the bow and in position for surrounding the edge and adjacent surfaces of the insole or other article to be bound. Furthermore, it will be seen that the adhesive-coated surface of the tape in its entire passage through the binder, and, in fact, in its entire travel from the time it leaves the reel until it reaches the point of application to the article required to be bound, is uninjured by anything and, in particular, nowhere contacts with the binder. The tape, as it moves in bowed form from the binder, passes between the feed rolls which are mounted in alignment with the tape as it leaves the binder and these rolls act to draw the tape through the binder and progressively press the tape into binding engagement with the article and advance the bound edge of the article.

50 As already pointed out, the conditioning of the adhesive coating of the tape is effected at a point well before the tape reaches the binder so

that whatever may be the character of adhesive employed, it may be properly conditioned so that it reaches the point of application in the most efficient condition for adhesion. In the case of a gutta-percha compound, or other thermoplastic adhesive, a hot, gaseous fluid such as hot air is most effective in conditioning the adhesive surface, but a certain time must elapse between the application of the heat and the application 5 of the adhesive tape to the article to be bound in order to obtain the best results. Furthermore, the hot gas or air must be applied uniformly and with best results by relatively slow, steady pressure. All these results are secured in the 10 present invention.

In the construction illustrated, a cylindrical casing 43 projects inwardly from the flange 3 and is provided with end plates 44 clamped to the cylinder ends by bolts 45. The interior of this 15 casing presents a cylindrical chamber. A cylindrical rotor 46 is mounted within the cylindrical chamber and carried by a shaft 47 eccentric to the axis of the cylindrical chamber and journaled in the head plates 44. This rotor is driven 20 by means later described. The eccentricity is such that the periphery of the rotor is in close proximity to the cylindrical chamber at one side. A plurality of blades 48 extends the entire length 25 of the chamber parallel with its axis and each is mounted for sliding movement in the rotor and yieldingly pressed as by the spring 49 into engagement with the cylindrical wall of the chamber.

A port 50 connected to a suitable supply of gaseous fluid opens into the chamber at a convenient point, as through a recess in the face of one of the end plates 44. When, as here, air is the gaseous fluid, the port is connected to a funnel-like device 51 provided with a sieve 52 and open to the atmosphere. A discharge port 30 53 opens from a recess in the face of the end plate 44 and thus from the chamber at a point where the space between the rotor and the cylindrical wall is near the minimum. This port 53 is connected to a nozzle, indicated generally at 35 54, facing the adhesive tape at a point soon after its passage from the reel. At least one of the blades 48 is always between the admission port 50 and the discharge port 53 so that gaseous fluid is prevented from passing directly across the 40 chamber from one port to the other.

In the construction illustrated, the discharge port 53 opens into a pipe 55 secured to the end plate 44 and this pipe extends into a collar 56 supporting a cylinder 57 closed at its outer end 58. The nozzle 54 opens from a pipe 59 extending 50 upward from a collar 60 on the cylinder 57 and both pipes 55 and 59 open through their respective collars into the interior of the cylinder 57. An electric heating element 61 is plugged 55 into the opposite end of the cylinder 57 and positioned to leave an annular space between it and an inner wall of the cylinder. This heating element has its terminals plugged at 62 into a switch box 63 secured in the inclined flange 4 of the machine. This switch box is provided with a telltale lamp 64 with a suitable switch 65 and the necessary current for operating the lamp and the heater is supplied by a cable 66 which may be connected to any suitable source.

It will thus be seen that when the current is turned on and the rotor is in operation, the blades 60 act successively to compress the fluid supplied to the cylindrical chamber and force it out under pressure through the discharge port past the electric heating element where it is heated and thence

under pressure out through the nozzle against the adhesive coating of the tape.

A further important feature resides in the manner in which the heat is applied to the tape to condition the coating by means of the nozzle. 5 The preferred form of nozzle 54 is illustrated in detail in Fig. 7. This nozzle presents a flat bed 80 over and close to which the adhesive-coated face of the tape 25 passes and upstanding side walls 81 and 82 between and close to which the tape 10 passes. A guide pin 83 projecting inward from the forward end of the side wall 82 extends over the tape and insures the tape remaining parallel with the flat bed 80 of the nozzle notwithstanding the twist the tape subsequently takes to engage the guide pin 33. The nozzle is secured in place on the upper end of the pipe 59 by a set screw 84. In the body of the nozzle immediately above the end of the pipe 59 is formed a cavity 85 preferably flaring upwardly in conical form and 15 extending nearly throughout the width of the tape. Thus it will be seen that the tape as it passes through the nozzle is practically passing through a small oven with the hot air or gas brought into contact progressively with substantially the entire area of the tape. Thus a very uniform heating or conditioning of the adhesive coating of the tape is secured with a minimum wastage of heat.

The elements of the machine may be driven 30 by any suitable means, but preferably both the rotor and the other elements of the machine operate simultaneously so that whenever the machine is stopped, as for inserting a new piece of work, and whenever the speed of the machine 35 changes as the character of the work may require, the supply of hot, gaseous fluid stops or changes therewith, thus maintaining the proper conditioning of the adhesive coating of the tape. Two constructions are illustrated for driving the machine. In Figs. 1 and 2, a pulley 67 driven from any suitable source of power, the starting and stopping of which and the variation of speed of which may be controlled in any usual manner, is carried by a shaft 68 journaled on the flange 3. 40 This shaft carries a pinion 69 meshing with and driving the gear 22 and this gear 22 in turn meshes with, and consequently drives, a pinion 45 70 on the rotor shaft.

In the construction shown in Fig. 8, a pulley 50 71 is mounted directly on the shaft of the rotor and this shaft carries a pinion 72 meshing with a large gear 73 corresponding with the gear 22 and driving the feed rolls in the same manner as 55 already described.

Having thus described the invention, what is claimed as new, and desired to be secured by Letters Patent, is:

1. A binder for presenting adhesive-coated tape to an edge to be bound thereby comprising 60 an exposed longitudinal convex guide with a longitudinal edge guide at its base acting, when the tape is drawn over the convex surface with its edge guided by said edge guide and with its non-adhesive side in contact with said surface, to bow the tape longitudinally, the entire space in front of the convex guide being open and unobstructed to leave the adhesive surface of the tape exposed throughout the convex surface of the guide, and an exposed concave recess in the end of the convex guide extending substantially at right angles thereto, the said recessed end acting, as the tape is drawn therethrough from the convex guide, to reverse the bow of the tape 65 70 and present it in position for surrounding an 75

edge and adjacent surfaces of an article with the adhesive surface untouched by the binder during its passage therethrough.

2. A binding machine for binding an edge with an adhesive-coated tape comprising a binder having an exposed longitudinal convex guide with a longitudinal edge guide at its base acting, when the tape is drawn over the convex surface with its edge guided by said edge guide and with its non-adhesive side in contact with said surface, to bow the tape longitudinally, an exposed concave recess in the end of the convex guide extending substantially at right angles thereto, the said recessed end acting, as the tape is drawn therethrough from the convex guide, to reverse the bow of the tape and present it in position for surrounding an edge and adjacent surfaces of an article with the adhesive surface untouched by the binder during its passage therethrough, and a pair of pressure feed rolls mounted in alignment with the tape as it leaves the binder acting to draw the tape through the binder, progressively press the tape into binding engagement with the article and advance the bound edge of the article.
3. A binding machine for binding an edge with an adhesive-coated tape comprising a support for a reel of tape, a binder acting to fold and present the tape with its adhesive side in binding position without contact of the adhesive side with the binder, a pair of pressure feed rolls acting to draw the tape from the reel through the binder and apply it to the edge to be bound, and adhesive conditioning means acting upon the adhesive coating of the tape between the reel and the binder at a point sufficiently remote from the binder to present the adhesive coating in required condition for application of the tape to

the edge of the article to be bound when it reaches the point of application.

4. A binding machine for binding an edge with a tape coated with a thermoplastic adhesive comprising a support for a reel of tape, a binder acting to fold and present the tape with its adhesive side in binding position without contact of the adhesive side with the binder, a pair of pressure feed rolls acting to draw the tape from the reel through the binder and apply it to the edge to be bound, a nozzle and means operated by the binding machine acting to force a hot, gaseous fluid by pressure through the nozzle against the adhesive coating, the said nozzle being located between the reel and the binder at a point sufficiently remote from the binder to cause the adhesive coating rendered tacky by the hot, gaseous fluid to be presented in required condition for application of the tape to the edge of the article to be bound when it reaches the point of application.

5. A binding machine for binding an edge with a tape coated with a thermoplastic adhesive comprising a support for a reel of tape, a binder acting to fold and present the tape with its adhesive side in binding position without contact of the adhesive side with the binder, a pair of pressure feed rolls acting to draw the tape from the reel through the binder and apply it to the edge to be bound, a nozzle located between the reel and the binder and presenting a chamber open against the adhesive side of the tape, and means connected to the nozzle chamber and operated by the binding machine acting to force a hot, gaseous fluid by pressure into the nozzle chamber and thence against the adhesive side of the tape as it is drawn past the nozzle.

WORTHINGTON S. BESSETT.
